UNITED STATES PATENT OFFICE.

FREDERICK WILLIAM GRELL, OF NEW YORK, N. Y., ASSIGNOR TO THE
AMERICAN HARD RUBBER COMPANY, OF NEW YORK.

DESIGN FOR A COMB.

SPECIFICATION forming part of Design No. 30,261, dated February 28, 1899.

Application filed October 18, 1898. Serial No. 693,923. Term of patent 14 years.

To all whom it may concern:

Be it known that I, FREDERICK WILLIAM GRELL, a citizen of the United States of America, residing at College Point, borough of 5 Queens, city and State of New York, have invented and produced a new and useful Design for Hair-Combs, of which the following is a specification.

My design consists, essentially, of a comb 10 having ribs extending across the sides of the back and coincidentally with the edges of the teeth.

In the accompanying drawings, Figure 1 is a view of a comb embodying my design. Fig. 15 2 is a view taken lengthwise of a portion of the back. Fig. 3 is a view taken lengthwise of a portion of the points of the teeth. Fig. 4 is a transverse section.

Similar letters of reference designate corresponding parts in all the views of the drawings.

A designates the back of the comb, and B some of the teeth. It will be seen that the

back of the comb is elliptical or ellipsoidal in cross-section and that the teeth taper sidewise to points or very small dimensions. The teeth at their widest portions are wider than the body of the back of the comb, and they consequently form ribs *b* upon the sides of the back of the comb. The spaces between these ribs are rounded, so as to form rounded 25 30 35 grooves.

The essential features of this design are the ribs projecting across the sides of the back of the comb.

What I claim as my design, and desire to secure by Letters Patent, is—

The design for a comb substantially as shown and described.

In testimony whereof I have signed my name to this specification in the presence of two subscribing witnesses.

FREDERICK WILLIAM GRELL.
